(57) **CLAIM**

The ornamental design for a trim reveal extrusion, as shown.

DESCRIPTION

FIG. 1 illustrates a perspective view of a trim reveal extrusion showing my new design; and,

FIG. 2 is an end elevational view thereof.

The trim reveal extrusion is shown with a symbolic break at its length. The appearance of any portion of the article between the break lines forms no part of the claimed design.

1 Claim, 1 Drawing Sheet
